UNITED STATES PATENT OFFICE.

JAMES WHITCOMB, OF GRAND ISLAND, NEBRASKA, ASSIGNOR OF ONE-SIXTEENTH TO HARLEY ANDREW HUDSON, ONE-SIXTEENTH TO RALPH MILO-HUDSON, ONE-SIXTEENTH TO JAMES H. HUGHES, ONE-SIXTEENTH TO OSCAR W. HART, AND ONE-SIXTEENTH TO HARRY C. BRYNER, ALL OF KEWANEE, ILLINOIS; ONE-EIGHTH TO TED UPTON, OF ANACONDA, MONTANA; AND ONE-SIXTEENTH TO HERMAN H. BOBENHOUSE, AND TWO-EIGHTHS TO VICTOR A. QUADAR, BOTH OF DENVER, COLORADO.

GAS ENGINE FOR AIRPLANES.

Application filed April 18, 1922. Serial No. 554,686.

To all whom it may concern:

Be it known that I, JAMES WHITCOMB, a citizen of the United States, residing at Grand Island, in the county of Hall and 5 State of Nebraska, have invented certain new and useful Improvements in Gas Engines for Airplanes, of which the following is a specification.

This invention relates to internal combustion engines of the double acting radial cylinder type.

An important object of the invention is to provide a novel form of intake manifold for supplying the combustible charge to the 15 cylinders.

A further object of the invention is to provide novel valve operating means embodying readily accessible cams and push rods.

20 Other objects and advantages of the invention will be apparent during the course of the following description.

In the drawings, I have shown one embodiment of the invention. In this showing,

25 Figure 1 is a plan view of the engine,

Figure 2 is a detail sectional view through the inner end of one of the cylinders and the elements associated therewith,

Figure 3 is a section taken on line 3—3 of 30 Figure 1,

Figure 4 is a section taken on line 4—4 of Figure 1,

Figure 5 is a section taken on line 5—5 of Figure 1, and,

35 Figure 6 is a detail perspective view of one of the valve rocker arms and associated elements.

In the drawings, wherein for the purpose of illustration is shown a preferred embodiment of my invention, the numeral 10 designates an outer arcuate support having horizontal base portions 11 at its opposite ends and preferably integral therewith. The support 10 is provided with a series of circular 40 openings 12 adapted to receive the outer ends of explosion cylinders 13. The cylinders 13 are provided near their outer ends with shoulders or collars 14, preferably integral therewith and adapted to bear against 45 the inner face of the support 10. The outer

ends of the cylinders 13 are closed by sealing heads 15 having flanges 16 extending outwardly beyond the cylinders 13 for a purpose to be described. The sealing heads 15 are further provided with tubular extensions 17 extending outwardly therefrom in the outer ends of which are mounted spark plugs 18 of any well known or preferred type.

The numeral 19 designates an inner substantially arcuate support, the ends of which are secured as by bolts 20 to the base portions 11 of the outer support. As clearly shown in Figures 2, 3 and 5, the inner support 19 contacts with the inner open ends of the cylinders 13 to form inner heads therefor. Bolts 21 are employed to securely clamp the cylinders to the outer heads 15 and the inner support 19, these bolts passing through the collars 14 and the outer support 10, as clearly shown in Figure 3. The support 19 is provided axially of each cylinder with an inwardly extending sleeve 22 provided upon their inner ends with shoulders 23 for a purpose to be described. The support 19 is further provided adjacent each sleeve 22 with an angular tubular extension 24, communicating with the inner end of the cylinder, in the outer ends of which are mounted the usual spark plugs 25. 50

The numeral 26 designates an outer casing or cover having an arcuate outer wall 27 and side walls 28. As shown in Figure 5, the casing 26 is substantially narrower than the support 10 and is secured thereto by bolts 29 passing through flanges 30 on the side walls 28 and through the support 10. The casing 26 is also secured to the base portions 11 of the outer support 10 by bolts 31 as shown in Figures 3 and 4. The casing 26 is provided with relatively large openings 32 in axial alinement with the cylinders 13, and these openings are normally closed by hand plates 33 secured to the casing 26 by bolts 34. The plates 33 are provided with openings 35 adapted to snugly receive the outer ends of the tubular extensions 17. From an examination of Figure 3 it will be apparent that the spark plugs 18 for the outer ends of the cylinders are readily ac- 55 60 65 70 75 80 85 90 95 100

cessible and that the outer cylinder heads 15 are readily accessible upon removal of the plates 33.

Each of the cylinders 13 is provided with 5 a piston 36 mounted to reciprocate therein and provided with inwardly and radially extending piston rods 37, mounted within the sleeves 22. The piston rods 37 are provided within the sleeves 22 with enlargements 38 having compression rings 39 thereon to prevent leakage of gases from the inner ends of the cylinders. The inner ends of the piston rods 37 are provided with heads 40 to which are pivotally connected 10 connecting rods 41 by wrist pins 42, as clearly shown in Figure 2.

The numeral 43 designates an inner casing which is substantially arcuate in form and is provided with openings 44 adapted to 20 slip over the ends of the sleeves 22 and to bear against the shoulders 23 thereon. The casing 43 is adapted to snugly engage the inner ends of the sleeves 22 to prevent leakage of gas therebetween. The numeral 44 designates a crank case which extends entirely across the lower portion of the engine 25 between the opposite sides of the support 19 and the lower ends of the casing 43 contact with the upper face of this crank case as at 30 45, see Figure 3. The open ends of the engine within the support 19 are closed by end plates 46 which are secured at their outer edges to flanges 47 formed upon the inner support 19 by bolts 48. The lower ends of 35 the end plates 46 are secured, as at 49, to flanges 50 formed upon the ends of the crank case 44. The ends of the inner casing 43 are secured to the end plates 46 as at 51. Thus it will be seen that the space 52 formed 40 between the inner support 19 and the inner casing 43 is entirely closed.

The numeral 53 designates a crank shaft having a single elongated crank 54 substantially centrally thereof to which are connected the inner ends of the connecting rods 41, in the usual manner. It will be obvious that the cylinders 13 are arranged in stepped formation to permit the connection of the inner ends of the connecting rods to the crank on the crank shaft. The crank shaft 53 is journaled in bearings 55 carried by the crank case 44 as shown in Figure 5.

As clearly shown in Figure 5, the outer ends of the cylinders are provided with exhaust ports 56 communicating with exhaust passages 57 through valve openings 58. The valve openings 58 are provided with exhaust valves 59 of the usual type provided with valve stems 60 extending downwardly 55 through bearings 61 formed in the lower portion of the exhaust passages 57 and through openings 62 formed in the inner supports 19. The lower ends of the exhaust valve stems are provided with heads 63 and 60 springs 64 are mounted between these heads

and the inner face of the support 19 to normally maintain the exhaust valves in closed position. The inner ends of the cylinders are provided with exhaust ports 65 normally closed by exhaust valves 66. The exhaust 70 valves 66 are provided with inwardly extending valve stems 67 having heads 68 formed upon the lower ends. As shown in Figure 5, the exhaust ports 65 communicate with exhaust passages 69. Springs 70 are 75 mounted between the heads 68 and the lower ends of the exhaust passages 69 to normally maintain the valves in closed position. The exhaust passages 57 are provided with exhaust pipes 71 extending outwardly through 80 the side walls 28 of the outer casing 26. The exhaust passages 69 are provided with outwardly extending exhaust pipes 72 which pass outwardly through the side plate 46. The exhaust pipes 71 and 72 are connected 85 with any well known or preferred type of muffler (not shown).

The outer ends of the cylinders are provided with intake ports 73 communicating with intake passages 74 provided with valve 90 seats 75 which are normally closed by intake valves 76. Radial intake pipes 77 are provided communicating between the intake passages 74 and the space 52. The valves 76 are provided with inwardly and radially 95 extending valve stems 78 preferably arranged centrally within the pipes 77 and journaled in spiders 79 carried in the lower ends of these pipes. The lower ends of the stems 78 are provided with heads 80 and 100 springs 81 are mounted between the heads 80 and the spiders 79 to normally maintain the valves 76 in closed position. The inner ends of the cylinders are provided with intake ports 82 in which are mounted intake 105 valves 83 provided with inwardly and radially extending valve stems 84 journaled in brackets 85 secured to the sleeves 22. The lower ends of the stems 84 are provided 110 with heads 86 and springs 87 are mounted between the heads 86 and the brackets 85 to normally maintain the valves 83 in closed position. As clearly shown in Figure 5 the ports 82 afford communication between the space 52 and the inner ends of the cylinders 115 13.

Plates 88 are mounted against the outer faces of the bearings 55 and are secured thereto by screws 89. The upper ends of the plates 88 are secured to the inner casing 120 43 by screws 90.

As shown in Figure 5, the plates 88 are mounted substantially parallel to and in spaced relation to the end plates 46.

Cam wheels 91 are rotatably mounted 125 upon the shafts 53 between the plates 46 and 88. The shaft 53 is provided with gears 92 secured thereto and adapted to mesh with gears 93 mounted upon stub shafts 94 journaled in bearings 95 in the end plates 46. 130

The gears 93 mesh with internal gears 96 formed within the cam wheels 91. The gears 96 have twice as many teeth as the gears 92 so that they rotate at one-half the speed of 5 the crank shaft 53.

The plates 88 are provided with bearings 97 which slidably receive push rods 98. The push rods 98 are provided at their lower ends with rollers 99 adapted to contact with 10 and roll upon suitable cams 100 formed upon the cam wheels 91. Upon the intake side of the engine, the push rods 98 are arranged in pairs and correspond in arrangement with the cylinders, one pair of push rods being 15 provided for each cylinder. The inner push rod 98 of each pair upon the intake side of the engine is adapted to contact at its upper end with an arm 101 secured to a rock shaft 102, the inner end of which is 20 provided with a second arm 103 which contacts with one of the heads 86. The outer push rod of each pair upon the intake side of the engine contacts at its upper end with an arm 104 secured to a rock shaft 105, the 25 inner end of which is provided with a second arm 106 which in turn contacts with one of the heads 80. The rock shafts 102 and 105 are journaled in bearings 107 carried by the inner face of the support 19. It will be 30 obvious that when one of the push rods 98 is raised by its corresponding cam, it in turn rocks its corresponding rock shaft to open one of the intake valves of one of the cylinders.

35 The arrangement of push rods 98 upon the exhaust side of the engine is similar to the arrangement of the push rods 98 upon the intake side of the engine as previously described. The outer push rod 98 of each 40 pair upon the exhaust side of the engine is adapted to contact at its upper end with an arm 108 secured to a rock shaft 109, the inner end of which is provided with a second arm 110 which contacts with one of the 45 heads 63. Similarly the inner push rod 98 of each pair upon the exhaust side of the engine is adapted to contact at its upper end with an arm 111 secured to a rock shaft 112 which is provided upon its inner 50 end with a second arm 113 which in turn contacts with one of the heads 68. The operation of the exhaust push rods 98 is the same as the operation previously described for the intake push rods 98 and no further 55 description thereof is believed to be necessary. The positions of the various cams 100 are arranged to open the various valves of the engine at proper intervals according to the practice in four cycle engines.

60 Detailed description of the operation of the present invention is believed to be unnecessary. Attention is called however to the arrangement by which the combustible fluid is supplied to the various cylinders of 65 the engine. Upon the intake side of the

engine an intake pipe 114 is provided which is connected with a suitable carburetor, not shown. The combustible fluid passes inwardly through the pipe 114 to the space 52 which is supplied at all times with an ample 70 supply of the combustible fluid. When the valves 83 are opened, outward movement of the pistons 36 draws a charge into the inner end of the cylinder directly from the space 52. When the valves 76 open inward movement of the pistons draws the combustible charge into the outer end of the cylinders through the intake pipes 77 from the space 52. Thus it will be seen that the space 52 75 serves as an intake manifold for each end 80 of all the cylinders and it will be further seen that the exhaust passages 69 serve to maintain the combustible charge within the space 52 in a heated condition at all times. When the exploded charge in the outer ends 85 of the cylinders has completed its work, the exhaust valves 59 open permitting the discharge of the burned gases through the exhaust passages 57 and exhaust pipes 71. Similarly when the exploded charges within 90 the inner ends of the cylinders have completed their work, the exhaust valves 66 open, permitting the escape of the burned gases through the exhaust passages 69 and exhaust pipes 72.

95 It will be obvious that the spark plugs for the outer ends of the cylinders are readily accessible while those for the inner ends of the cylinders may be removed for cleaning or replacing by removing the end plates 46. 100 The provision of tubular extensions 24 and 17 removes the firing points of the spark plugs from contact with oil within the cylinders and serves to more efficiently ignite the charges within the cylinders.

105 It is to be understood that the form of my invention herewith shown and described is to be taken as a preferred example of the same, and that various changes in the shape, size, and arrangement of parts may be resorted to without departing from the spirit of the invention or the scope of the subjoined claims.

110 Having thus described my invention, I claim:

115 1. An internal combustion engine comprising a plurality of cylinders, a casing having one wall adapted to form a support for and a closure for one end of each of said cylinders, means for supplying combustible fluid to the interior of said casing, valve mechanism for admitting the combustible fluid into the ends of the cylinders through said casing at proper intervals, a piston mounted in each of said cylinders, a piston rod connected to each of said pistons and extending through said casing, a crank shaft, a connecting rod connecting the crank shaft with each of said piston rods, means for firing the combustible charges within the 120

125

130

cylinders, and means for exhausting burned gases from the cylinders at proper intervals.

2. An internal combustion engine comprising a plurality of cylinders, an arcuate support provided with openings adapted to receive the outer ends of said cylinders, cylinder heads adapted to close the outer ends of said cylinders, a casing having one wall adapted to form a support and a closure for one end of each of said cylinders, means for supplying combustible fluid to the interior of said casing, valve mechanism for admitting the combustible fluid into the ends of the cylinders through said casing at proper intervals, a piston mounted in each of said cylinders, a piston rod connected to each of said pistons and extending through said casing, a crank shaft, a connecting rod connecting the crank shaft with each of said piston rods, means for firing the combustible charges within the cylinders, and means for exhausting burned gases from the cylinders at proper intervals.

3. An internal combustion engine comprising a plurality of cylinders, an arcuate support provided with openings adapted to receive the outer ends of said cylinders, cylinder heads adapted to close the outer ends of said cylinders, a casing having one wall adapted to form a support and a closure for one end of each of said cylinders, means for supplying combustible fluid to the interior of said casing, an intake valve mounted in each end of each of said cylinders and communicating with the interior of said casing, valve operating mechanism for opening said intake valves at proper intervals, a piston mounted in each of said cylinders, a piston rod connected to each of said pistons and extending through said casing, a crank shaft embodying a single crank, a connecting rod connecting the single crank of the crank shaft with each of said piston rods, means for firing the combustible charges within the cylinders, and means for exhausting burned gases from the cylinders at proper intervals.

4. An internal combustion engine comprising an outer arcuate support including base portions, an inner arcuate support spaced from said outer support and secured to the base portions thereof, a plurality of cylinders radially mounted between said supports, said inner support forming the inner heads of said cylinders, a head mounted upon the outer end of each cylinder, a tubular extension formed on each of said heads and communicating with the outer ends of said cylinders, a tubular extension carried by said inner support adjacent each cylinder and communicating with the inner ends thereof, a spark plug mounted in each of said tubular extensions, an arcuate plate connected at its lower ends to said inner support, the space between said plate and said inner support being closed by

side and bottom members to form an intake manifold, intake valves mounted in opposite ends of said cylinders and communicating with said manifold, a piston mounted in each of said cylinders, a piston rod carried by each of said pistons and extending inwardly through said manifold, a crank shaft, connecting rods connected between said piston rods and said crank shaft, exhaust valves for controlling the exhaust gases from opposite ends of each of said cylinders, and valve mechanism for operating said intake and exhaust valves.

5. An internal combustion engine comprising an outer arcuate support including base portions, said support being provided with openings, an inner arcuate support spaced from said outer support and secured to the base portions thereof, a plurality of cylinders radially mounted between said supports, and having their outer ends projecting through the openings in said outer support, said inner support forming the inner heads of said cylinders, a head mounted upon the outer end of each cylinder, a tubular extension formed on each of said heads and communicating with the outer ends of said cylinders, a tubular extension carried by said inner support adjacent each cylinder and communicating with the inner ends thereof, a spark plug mounted in each of said tubular extensions, a sleeve carried by said inner support axially of each cylinder and extending inwardly thereof, an arcuate plate connected between the inner ends of said sleeves, the space between said plate and said inner support being closed by side and bottom members to form an intake manifold, the inner ends of said cylinders being provided with intake ports communicating directly between said intake manifold and inner ends of said cylinders, the outer ends of said cylinders being provided with an intake port, an intake pipe communicating between each of said outer intake ports and said intake manifold, intake valves adapted to normally close each of said intake ports, a piston mounted in each of said cylinders, a piston rod carried by each of said pistons and extending inwardly through said sleeves, a crank shaft, connecting rods connected between said piston rods and said crank shaft, exhaust valves for controlling the exhaust gases from opposite ends of each of said cylinders, and valve mechanism for operating said intake and exhaust valves.

6. An internal combustion engine comprising an outer arcuate support including base portions, said support being provided with openings, an inner arcuate support spaced from said outer support and secured to the base portions thereof, a plurality of cylinders radially mounted between said supports, the outer ends of said cylinders projecting through the openings in said outer

support, said inner support forming the inner heads of said cylinders, a head mounted upon the outer end of each cylinder, a tubular extension formed on each of said heads and communicating with the outer ends of said cylinders, a tubular extension carried by said inner support adjacent each cylinder and communicating with the inner ends thereof, a spark plug mounted in each of said tubular extensions, a sleeve carried by said inner support axially of each cylinder and extending inwardly thereof, an arcuate plate connected between the inner ends of said sleeves, the space between said plate and said inner support being closed by side and bottom members to form an intake manifold, each of said cylinders being provided in its inner end with an intake port communicating with said intake manifold, each of said cylinders being provided in its outer end with an intake port, an intake pipe communicating between each of said outer intake ports and said intake manifold, intake valves adapted to normally close each of the said intake ports, a piston mounted in each of said cylinders, a piston rod carried by each of said pistons and extending inwardly through said sleeves, a crank shaft embodying a single crank, bearings for said crank shaft arranged on opposite sides of said crank, connecting rods connected between said piston rods and the crank on said shaft, exhaust valves for controlling the exhaust gases from opposite ends of each of said cylinders, cam wheels embodying cams mounted upon said crank shaft outwardly of said bearings, and means connected between said cam wheels and said valves for opening the valves at proper intervals.

5 25 30 35

In testimony whereof I affix my signature 40 in presence of two witnesses.

JAMES WHITCOMB.
